US00D633082S

(12) **United States Design Patent**
Ragde, Jr. et al.

(10) **Patent No.:** **US D633,082 S**
(45) **Date of Patent:** **** Feb. 22, 2011**

(54) **PORTABLE SPEAKER SYSTEM**D516,579 S 3/2006 Nakamura
D517,364 S 3/2006 Nieves(75) Inventors: **Jorge V. Ragde, Jr.**, Canyon Country, CA (US); **Timothy J. Jacobus**, Agoura Hills, CA (US)

(Continued)

(73) Assignee: **Portable Sound Laboratories, Inc.**, Van Nuys, CA (US)

FOREIGN PATENT DOCUMENTS

DE 200600533 U1 7/2006

(**) Term: **14 Years**

(Continued)

(21) Appl. No.: **29/368,927**

Primary Examiner—Nanda Bondade

(22) Filed: **Aug. 31, 2010**

(74) Attorney, Agent, or Firm—Blakely, Sokoloff, Taylor & Zafman, LLP

(51) **LOC (9) Cl.** **14-01****CLAIM**(52) **U.S. Cl.** **D14/214**; D14/217

The ornamental design for portable speaker system, as shown and described.

(58) **Field of Classification Search** **D14/204, D14/211–217, 172, 188, 474, 496; D3/218, D3/301; D6/632–635; 181/143–148, 150, 181/157, 198–199, 151, 153; 381/300–302, 381/306, 333, 345, 361–364, 385–388, 332, 381/336, 689, 679; 224/576, 929**

See application file for complete search history.

DESCRIPTION(56) **References Cited**

FIG. 1 is a rear perspective view of a portable speaker system.

U.S. PATENT DOCUMENTS

FIG. 2 is a front perspective view of the portable speaker system FIG. 1.

FIG. 3 is a rear elevational view of the portable speaker system of FIG. 1.

FIG. 4 is a front elevational view of the portable speaker system of FIG. 1.

FIG. 5 is a top plan view of the portable speaker system of FIG. 1.

FIG. 6 is a bottom plan view of the portable speaker system of FIG. 1; and,

FIG. 7 is a side elevational view of the portable speaker system of FIG. 1.

The broken lines in the figures are for environmental purpose only and form no part of the claimed design.
